[57] **CLAIM**

The ornamental design for textile pile fabric, substantially as shown and described.

DESCRIPTION

FIG. 1 is a top plan view of a textile pile fabric showing a first embodiment of my new design with the lower half of the view illustrating one repeat of the design and the upper half of the view illustrating a substantially complete second repeat, and with the upper and lower halves being further indicated by the marginal repeat boundary lines;

FIG. 2 is a top plan view of a textile pile fabric showing a second embodiment of my new design with the lower half of the view illustrating approximately one repeat of the design and with the upper half of the view illustrating approximately a second repeat, and with the upper and lower repeats being further indicated by the marginal repeat boundary lines; and

FIG. 3 is a top plan view of the embodiment of my new design shown in FIG. 2, but in a somewhat reduced scale to thereby illustrate several repeats in regular succession as indicated by the marginal repeat boundary lines in both the horizontal and vertical directions.
